(57) **CLAIM**

The ornamental design for a packaging box, as shown and described.

DESCRIPTION

FIG. 1 is a perspective view of a packaging box showing my new design;

FIG. 2 is a front view thereof, a rear view thereof being identical to the front view;

FIG. 3 is a right side view thereof, a left side view thereof being identical to the right side view; and,

FIG. 4 is a top view thereof, a bottom view thereof being identical to the top view.

In the drawings, the broken lines showing the conventional packaging box are for illustrative purpose only and form no part of the claimed design.

1 Claim, 4 Drawing Sheets

FIG. 1

FIG.2

FIG. 3

FIG. 4
